(57) **CLAIM**

The new, original and ornamental design for an eyewear holder, as shown and described.

DESCRIPTION

FIG. 1 is a top plan view of a first embodiment of an eyewear holder showing my new design, the design also being a clip for eyewear, an accessory for hanging eyewear, and a clip for attachment to clothing or bags to enable an object such as eyeglasses and sunglasses to be hung thereon;

FIG. 2 is a front, elevational view thereof;

FIG. 3 is a bottom plan view thereof;

FIG. 4 is a right side elevational view thereof, the left side elevational view thereof being a mirror image;

FIG. 5 is a rear elevational view thereof;

FIG. 6 is a front, right side perspective view thereof;

FIG. 7 is a top plan view of a second embodiment of an eyewear holder showing my new design, the design also being a clip for eyewear, an accessory for hanging eyewear, and a clip for attachment to clothing or bags to enable an object such as eyeglasses and sunglasses to be hung thereon;

FIG. 8 is a front, elevational view thereof;

FIG. 9 is a bottom plan view thereof;

FIG. 10 is a right side elevational view thereof, the left side elevational view thereof being a mirror image;

FIG. 11 is a rear elevational view thereof;

FIG. 12 is a front, right side perspective view thereof;

FIG. 13 is a top plan view of a third embodiment of an eyewear holder showing my new design, the design also being a clip for eyewear, an accessory for hanging eyewear, and a clip for attachment to clothing or bags to enable an object such as eyeglasses and sunglasses to be hung thereon;

FIG. 14 is a front, elevational view thereof;

FIG. 15 is a bottom plan view thereof;

FIG. 16 is a right side elevational view thereof, the left side elevational view thereof being a mirror image;

FIG. 17 is a rear elevational view thereof;

FIG. 18 is a front, right side perspective view thereof;

FIG. 19 is a top plan view of a fourth embodiment of an eyewear holder showing my new design, the design also being a clip for eyewear, an accessory for hanging eyewear, and a clip for attachment to clothing or bags to enable an object such as eyeglasses and sunglasses to be hung thereon;

FIG. 20 is a front, elevational view thereof;

FIG. 21 is a bottom plan view thereof;

FIG. 22 is a right side elevational view thereof, the left side elevational view thereof being a mirror image;

FIG. 23 is a rear elevational view thereof; and,

FIG. 24 is a front, right side perspective view thereof.
